UNITED STATES PATENT OFFICE.

JOSEPH I. SMITH, OF OGDEN, UTAH.

COMBINED CAMP BOX AND BENCH.

Application filed March 24, 1926. Serial No. 97,107.

My invention relates to a combined camp box and bench.

In accordance with my invention, I provide a box which is adapted to be mounted upon the running board of an automobile, and detachably held thereon by any suitable means. This box is equipped at its ends with socket handles, which are adapted to receive legs, whereby the box may be supported upon the ground, at a suitable elevation, and will then function as a bench, table or the like. The device is of simple construction, and the legs are formed in pairs which are permanently connected, and collapsible, so that they will occupy the least space when not in use.

I further provide means whereby the box may be quickly and securely detachably mounted upon the running board.

In the accompanying drawings, forming a part of this specification, and in which like numerals are employed to designate like parts throughout the same,

Figure 1 is a perspective view of a device embodying my invention, showing a box mounted upon the running board of an automobile,

Figure 2 is a perspective view of the device showing the legs employed to hold the box element elevated,

Figure 3 is an end elevation of the same,

Figure 4 is a side elevation of a pair of legs, in the open position,

Figure 5 is a similar view, showing the legs collapsed,

Figure 6 is a vertical section taken on line 6—6 of Figure 3, the legs being omitted,

Figure 7 is a fragmentary plan view of a pair of the legs,

Figure 8 is a perspective view of the box, showing the detachable connecting means,

Figure 9 is a transverse vertical section taken on line 9—9 of Figure 8, and,

Figure 10 is a perspective view of the elements of the connecting means, the same being separated for the purpose of illustration.

In the drawings, wherein for the purpose of illustration, is shown a preferred embodiment of my invention the numeral 10 designates a box element, having a lid or top 11, which may be hinged thereto, and held closed by a lock 12 or other suitable device. The box element 10 is detachably clamped to the running board 13 of an automobile.

Arranged at each end of the box element 10 are handle-sockets 13, which may be formed of sheet metal, or other suitable material. These handle-sockets are generally inverted U-shaped, with their tops and bottoms open. 60 These handle-sockets have flanges 14, attached to the ends of the box element by screws or bolts 15. The lower edge of the handle-socket is preferably rolled, as indicated at 16, providing a convenient grip. 65

Adapted for insertion within each handle-socket 13 is a pair of inclined upwardly converging legs 17, which are permanently pivotally connected at their upper ends, by means of a leaf hinge 18, secured to the 70 sides thereof, as shown. At their upper ends, the legs 17 have parallel faces 19, which are adapted to contact with each other, thereby taking most of the strain off of the hinge. The legs 17 are preferably cut 75 away, beneath and adjacent to the hinge 18, at 20, affording a hand holding space or recess.

In Figures 8 to 10, inclusive, I have shown connecting devices which are particularly 80 well adapted for securing the box 10 to the running board. These connecting devices embody straps or bars 21, preferably formed of metal, which are arranged near the ends of the box element 10, and rigidly attached 85 thereto by bolts 22. These straps or bars 21 extend transversely beneath the bottom of the box element with spacing elements 23 between the same which are also held in place by the bolts 22. At their outer ends, 90 these straps or bars are bent downwardly at a right angle affording a lateral extension or ear 24, adapted to be arranged adjacent to the vertical ears 25 which are bolted to the bottom of the running board 95 13, at its outer edge, as shown at 26. The ears 24 and 25 are apertured for receiving clamping bolts 27, preferably carrying winged nuts 28.

Mounted upon the top of the running 100 board 13 and rigidly secured thereto near its inner edge are strap-sockets 29, positioned in transverse alinement with the stationary ears 25. These strap-sockets are adapted to slidably receive the inner ends 105 of the straps or bars 21.

The box element 10 may be mounted upon the running board 13, and detachably clamped thereto by any suitable means, preferably by means of the connecting devices 110

shown in Figures 8 to 10, inclusive. This box element may be removed from the running board and a pair of the legs 17 inserted in each of the handle-sockets 13. 5 When within these handle-sockets, the pairs of legs 17 support a box element, at a suitable elevation, which may be used as a bench, or as a table. The cut away portions 20 provide a suitable recess or space so that 10 the hand may be inserted within the handle-socket 13, for effecting a convenient manual shifting of the box element. When the legs are withdrawn from the handle-sockets, these handle-sockets may then be used as 15 ordinary handles. The legs in each pair are collapsible, Figure 5, and may be packed within the box element and will take up the least space.

It is to be understood that the form of my 20 invention, herewith shown and described, is to be taken as a preferred example of the same, and that various changes in the shape, size and arrangement of parts, may be resorted to without departing from the spirit

of my invention, or the scope of the sub- 25 pined claim.

Having thus described my invention, I claim:

A device of the character described, comprising a member to be supported, a handle-socket secured to the member and tapering upwardly, a pair of upwardly converging legs adapted to have their upper ends inserted within the handle-socket, such upper ends having contacting edges which are 35 adapted to be substantially vertical when the legs are in the upright position, and a hinge connecting the upper ends of the legs and having its axis of turning movement substantially parallel with the contacting 40 edges, the arrangement of the hinge being such that one leg is adapted to be turned generally upon its longitudinal axis and to be folded flat upon the side of the companion leg. 45

In testimony whereof I affix my signature.

JOSEPH L. SMITH.
